L. R. DEXTER, OF WHITEFIELD, NEW HAMPSHIRE.

Letters Patent No. 88,017, dated March 23, 1869.

IMPROVEMENT IN WRENCHES.

The Schedule referred to in these Letters Patent and making part of the same.

To all whom it may concern:

Be it known that I, L. R. DEXTER, of Whitefield, in the county of Coos, and State of New Hampshire, have invented a new and improved Wrench; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

This invention relates to a new and improved wrench, and is more especially designed to be used in connection with wagons or carriages, although it is applicable to other purposes.

The object of the invention is to obtain a wrench which may, with the greatest facility, be adapted to screwing up, or unscrewing nuts which vary in size, or screwing up, or unscrewing screws, the heads of which vary in size.

The invention consists in the employment, or use of a taper-socket, having a handle fitted in it, and the socket provided with a spring-clamp, to grasp the nut, or screw-head, all being constructed and arranged substantially as hereinafter fully shown and described.

In the accompanying sheet of drawings—

Figure 1 is a side view of my invention.

Figure 2, a side sectional view of the same, the plane of section passing through the centre.

Figure 3, a plan or top view of the same.

Figure 4, a detached view of the spring-clamp.

Similar letters of reference indicate corresponding parts in the several drawings.

A represents a socket, which is of taper quadrilateral form, and may be constructed of malleable cast-iron, or any other suitable material.

Through the upper part of this socket, a handle, B,

passes, and is secured in position by a pin, C, which extends through the handle, the pin, in connection with a crook, or bend, a^x, in the handle, securing the latter in position, as will be fully understood by referring to fig. 3.

D represents a spring-clamp, which is of curved form, as shown clearly in fig. 4, and is secured, by a pin, a, to the exterior of the socket A, near its lower end, as shown in fig. 1.

The upper bent, or curved part of this spring-clamp bears against the handle B, while its lower end bears against the nut, or head of the screw to be operated upon, and clamps the latter in position.

The lower end of the spring passes through a notch, b, in the lower part of the socket.

This spring-clamp, in connection with the taper-form of the socket, renders the device capable of being adjusted to different-sized nuts, or screw-heads, the spring, in case of a nut, or screw-head being too small, pressing the latter, and keeping its edges, at three sides, in contact with three sides of the socket.

The handle B, in consequence of extending entirely through the socket, and projecting from two opposite sides of it, admits of the application of two hands to the wrench, and facilitates the starting of a nut or screw, when the same turns hard, and also admits of said parts being tightly screwed up.

Having thus described my invention,

What I claim as new, and desire to secure by Letters Patent, is—

The combination of the taper-socket A, handle B, and the spring-clamp D, all constructed and arranged substantially in the manner as and for the purpose set forth.

L. R. DEXTER.
